UNITED STATES PATENT OFFICE.

HUGH M. MARSH, OF CHICAGO, ILLINOIS.

BROOM.

1,138,303.

Specification of Letters Patent.

Patented May 4, 1915.

Application filed February 6, 1914. Serial No. 816,923.

To all whom it may concern:

Be it known that I, HUGH M. MARSH, a citizen of the United States, and resident of Chicago, county of Cook, and State of Illinois, have invented certain new and useful Improvements in Brooms, of which the following is a specification, and which are illustrated in the accompanying drawings, forming a part thereof.

10 The invention relates to brooms, mops and the like and more particularly to those in which the parts of the head are permanently secured between a pair of clamping plates having shanks which serve to form a handle

15 socket. Brooms of the kind referred to are more especially used in shops, warehouses and for other heavy service. For these purposes they are usually purchased in quantities and 20 while great strength is required it is nevertheless desirable that the handle and head should be detachably connected to permit a single handle to be used repeatedly. A detachable connection of the handle and head 25 also reduces the amount of space required for the storage of a quantity of brooms whereby a large number may be more conveniently stored for use in an emergency, as upon a heavy fall of snow.

30 The present invention accordingly contemplates an improved construction of the said clamping plates and of the means for connecting them to each other and to the handle.

35 The object of the invention is to provide a broom or mop of inexpensive, yet efficient construction and of improved appearance.

In the accompanying drawings—Figure 1 is a front elevation of a broom embodying 40 the features of improvement provided by the invention; Fig. 2 is a central longitudinal sectional view of the same, partly in elevation; Fig. 3 is a perspective view of the broom, showing a cover for inclosing the 45 clamping plates; and Fig. 4 is a detail sectional view taken on the line 4—4 of Fig. 1.

In carrying out the invention a pair of mating clamping plates 10, 11, having oppositely bowed registering shanks 12 and 13, 50 are provided. In event the article to be constructed is a corn broom, these plates are applied with great pressure to a body of corn strands, as 14, adjacent one end of the same.

55 Preferably the plates 10 and 11 take the general shape and outline of the inner end portion of a broom head. In order that they

may have the required strength while still being formed of relatively light metal, and to insure the corn strands being firmly held between them, each plate is desirably 60 formed with outwardly bowed upper and lower transverse ribs 15, 16, and with a longitudinal rib, as 17, 18, at each side. A still further increased hold of the plates 10 and 11 upon the body 14 of corn strands may be 65 obtained by forming the plates with intermediate transverse ribs, as 19 and 20, with the rib, as 19, of one plate bowed outwardly, and the rib, as 20, of the other plate bowed inwardly; also by providing an instanding 70 lip, as 21 (Fig. 2), upon the lower edge of each of the plates 10 and 11 at each side of the same. The effect of the ribs 19, 20, is to flex the body 14 of corn strands intermediate the lines of engagement therewith of the 75 upper and lower portions of the plates 10 and 11.

For permanently connecting the plates 10 and 11, they are preferably provided with a plurality of intercalating tongues, as 22, 80 and apertures, as 23, adjacent each side. As shown, the tongues 22 are all formed upon the plate 11, the apertures 23 being in the plate 10. When the plates are pressed together the tongues 22 are each folded about 85 the adjacent side of the body 14 of corn strands, over the edge of the opposite plate, and are then thrust into the corresponding aperture 23. If the tongues are made of sufficient length, the curving of the same continues upon entering the corn strands between the plates, and the end of the tongue becomes engaged with the plate 10 upon the inside adjacent the aperture 23, as appears 90 at 24 (Fig. 4).

A permanent rigid connection of the plates 10 and 11 between their side edges is also essential when broom corn is used for the body 14. As shown, such a connection is obtained by mounting a ring 25 about the shanks 12 100 and 13 adjacent their inner ends. To prevent displacement of the ring, each of the shanks is desirably depressed, as at 26 (Fig. 2), at the point where it is engaged by the ring.

The shanks 12 and 13 of the plates 10 and 11 provide a socket for receiving the handle, as 27. A firm, but detachable connection of the handle is conveniently obtained by permanently mounting a pin 28 transversely through the handle, and by providing an 105 aperture, as 29, in each of the shanks 12 and 13 for receiving the ends of the pin. A com-

pression ring 30 then desirably runs on the shanks 12 and 13. As shown, the handle 27 has an annular shoulder 31 of greater height than the thickness of the shanks 12, 5 13, to serve as a stop for preventing the compression ring 30 passing upwardly upon the handle beyond the higher ends of the shanks. By making the pin 28 of sufficient length to project through the shanks 12 and 10 13, and by rounding the ends of the pin, the compression ring 30 may be forced upwardly beyond the pin and will then be held between the pin and the annular shoulder 31. For removing the handle the compression 15 ring 30 must be driven downwardly to pass over the rounded ends of the pin 28. Accidental displacement of the handle accordingly is effectively prevented.

In applying the handle 27 to the broom 20 head, the end of the handle is desirably entered between the shanks 12 and 13 when the compression ring 30 is at the lower ends of the shanks and the handle is so turned as to cause the ends of the pin 28 to pass 25 into the spaces, as 32 (Fig. 3), between the two shanks. When the shoulder 31 comes into engagement with the ends of the shanks 12 and 13, the handle will be rotated to bring the pin 28 into alinement with the 30 apertures 29. The compression ring 30 is then driven upwardly over the ends of the pin. The rounding of the ends of the pin 28 enables them to engage the edges of the shanks 12 and 13 to spread the shanks and 35 permit the pin to pass under them during the said rotation of the handle. Similarly in withdrawing the handle after the compression ring 30 has been driven downwardly over the ends of the pin 28, the handle 40 is rotated, the ends of the pin thereby separating the shanks and passing under them until the intervening spaces, as 32, are reached.

The introduction of the end of the handle 45 27 into the space between the shanks 12, 13, of the plates 10, 11, is facilitated by providing the handle with a sharp point 37 (Fig. 2). Furthermore, to enable the handle to be firmly seated in that part of the socket 50 which is within the fixed ring 25, the handle is provided with an annular shoulder 38 adjacent the point 37, that part of the handle which is beyond the shoulder being of reduced diameter. It will be understood 55 that in the construction of the broom head, the space inclosed by the shanks 12 and 13 is freed from projecting ends of corn strands by the use of a drill having a point conforming to the point 37 of the handle.

60 A covering 33 may be applied to the broom head for inclosing the clamping plates 10 and 11, if desired. The covering is preferably of sheet material as cloth or a stiff fibrous material, which may be shaped 65 to conform to the end of the broom head by

heat and pressure. As shown, the cover 33 is apertured at 34 to pass the handle 27 and the shanks 12, 13, of the plates 10 and 11.

If desired cement may be used in securing the cover 33 to the plates 10 and 11, and as 70 a further securing means a long nail, as 36, may be driven through the cover 33 and into the body 14 of corn strands between the plates 10 and 11 at each side. The cover 33 not only improves the appearance of the 75 article, but also adapts it to use in the household by protecting the plates 10, 11, against injury to articles of furniture and the like.

I claim as my invention—

1. In a device of the kind described, in 80 combination, a body of strands, a pair of clamping plates compressing the strands and having oppositely bowed registering shanks forming a handle socket, means permanently connecting the ends of the plates 85 and binding them together upon the strands, a fixed ring encircling the said shanks at their inner ends and binding the plates together intermediate the ends of the plates, a handle fitting the said socket between the shanks, and means detachably connecting the handle and shanks.

2. In a device of the kind described, in 90 combination, a body of strands, a pair of clamping plates compressing the strands and having oppositely bowed registering shanks forming a handle socket, means extending about the margins of the body of strands permanently connecting the ends of the plates and binding them together upon 95 the strands, a fixed ring encircling the said shanks at their inner ends and binding the plates together, the said ring being the only means permanently connecting the plates intermediate their ends, a handle fitting the 100 said socket between the shanks, and releasable means compressing the said shanks upon the handle.

3. In a device of the kind described, in 110 combination, a body of strands, a pair of permanently connected clamping plates compressing the strands and having elastic oppositely bowed registering shanks forming a handle socket and one of said shanks being apertured adjacent its outer end, a 115 handle having an end of reduced diameter for entering the said socket between the shanks and a shoulder higher than the thickness of the shanks for engaging the outer ends of the shanks, a pin set into the handle in line with the said shank aperture and projecting from the handle a greater distance than the thickness of the apertured shank, and a compressing ring running on the shanks and movable over the projecting 120 end of the said pin into the space between the pin and the said handle shoulder.

4. In a device of the kind described, in 125 combination, a body of strands, and a pair of clamping plates compressing the strands 130

and having intercalating fingers and apertures, each of the said fingers being folded about the margins of the body of strands and of the apertured plate and entering the 5 body of strands through the plate aperture and engaging the apertured plate upon the inside adjacent the aperture.

5. In combination, a broom body of corn strands and a handle, a pair of clamping jaws compressing the body and having oppositely bowed registering shanks forming a split tubular socket for receiving the handle, one of the shanks being apertured and the handle being provided with a reduced end 10 15 portion adapted to enter the socket and with a shoulder of greater depth than the thickness of the shanks adapted to abut against the ends of the shanks, a pin having a rounded end projecting from the reduced end portion of the handle a greater distance than the thickness of the apertured 20

shank and adapted to enter the aperture of such shank, and a compressing ring sliding on the shanks, such ring being adapted to yieldingly pass over the projecting rounded end of the pin and to abut against the shoulder on the broom handle. 25

6. In a device of the kind described, in combination, a body of strands, a pair of clamping plates compressing the strands, the two plates being formed with a registering rib and groove extending transversely across the inner faces of the plates intermediate their ends whereby the strands are flexed intermediate the points of engagement therewith of the marginal portions of the plates and means permanently connecting the plates. 30 35
